UNITED STATES PATENT OFFICE

GRANT WHEAT, OF MARLBORO, MASSACHUSETTS, ASSIGNOR TO KOEHLER MANUFACTURING COMPANY, OF MARLBORO, MASSACHUSETTS, A CORPORATION OF MASSACHUSETTS

MINER'S LAMP

Application filed November 22, 1928. Serial No. 149,890.

This invention relates to lamps of the general type used by miners, and artisans and known as "miners' lamps."

Such lamps usually include a head piece 5 which is mounted on the miner's cap, this head piece containing one or more electric lamps which are supplied with current from a battery that usually is slung to the miner's belt. Lamps of this type as heretofore constructed have been of very limited candle power, and it is an important object of this invention to devise a lamp which will give the miner much greater illumination than prior lamps without unduly increasing the size or weight of the apparatus. The invention also aims to devise means for cutting off the current automatically from the electric lamps upon the breaking of the apparatus so that danger of igniting combustible gases 15 present in the mine will be minimized.

The nature of the invention will be readily understood from the following description when read in connection with the accompanying drawings, and the novel features will be particularly pointed out in the appended claims.

In the drawings,

Figure 1 is a perspective view of a head piece constructed in accordance with the present invention, this head piece being shown mounted on a miner's cap;

Fig. 2 is a front elevation of the head piece shown in Fig. 1;

Fig. 3 is a cross-sectional view through the head piece shown in Fig. 1;

Figs. 4 and 5 are front and perspective views, respectively, of the insulating casing and parts contained therein; and

Fig. 6 is a detail view of the main lamp bulb base, showing the socket and the contacts for the bulb.

The lamp shown includes many of the features of my prior Patent No. 1,361,557, granted December 7, 1920, and, in addition, 45 contains certain improvements. As shown, the lamp comprises a head piece which includes a lamp casing 2 preferably made of some insulating material, such as hard rubber, this casing having a metal bracket 3 se- 50 cured thereto by means of which it is remov-

ably fastened to a front plate 4 on a miner's cap 5.

Mounted within the lamp casing 2 is a main lamp 6 and an auxiliary lamp 7. The main lamp is of much larger candle power than has been used heretofore in miners' lamps, so far as I am aware. A lamp of fifteen candle power may conveniently be used here, while the auxiliary lamp usually is of six candle power, which is the common size heretofore used in apparatus of this character. In order to mount these lamps within a small space and within a lamp casing of suitable design, it is preferable to support the main lamp 6 vertically and the auxiliary lamp 7 60 horizontally and immediately below the main lamp. For this purpose a socket 8 is provided in the upper part of the casing 2 to receive the base of the lamp 6, this socket comprising a cup-shaped metal member 65 mounted on the free end of a spring arm 9 which is secured to a plate 10 that is anchored in the casing. One wire or lead 12, Fig. 4, of the current supplying conductor 13 is secured to the plate 10 by a screw 14 70 so that current is conducted by the lamp socket 8 to the metal shell which forms the outer part of the base of the lamp 6. The central terminal at the tip of the lamp base normally is held against a metal strip or plate 15 which is embedded in the material of the casing 2 and is provided with an extension 15', Fig. 4, which is secured rigidly 75 to the inside of the casing by screws. This plate may be electrically connected to the other wire 16 of the supply conductor 13 through an electric switch which, as shown, 80 consists of a rotary metal plate 17, Figs. 4 and 5, lying in contact with a stationary plate 18 to which the wire 16 is connected by a screw 19. The plate 17 is mounted on the inner end of a short shaft to which a handle 20, Fig. 1, of insulating material is secured. This handle consists of a disk of hard rubber 85 or other insulating material having a roughened edge so that it may conveniently be turned to rotate the movable switch member 17 into or out of contact with the stationary plate 15'. The elements for supporting the auxiliary 90

100

- lamp are much like those shown in my prior patent above designated, and include a cup-shaped metal socket 21 supported on the end of a spring arm which is connected to the plate 10 by a metal strip 22, Fig. 4. The cup 21 engages the metal shell on the base of the lamp 7 while the terminal at the tip of this lamp is engaged by a stationary contact 23 forming part of a plate 24 which is secured to the inside of the casing where it will cooperate with the movable member 17 of the switch above described. In order to hold the auxiliary lamp 7 in its socket with its end terminal in engagement with the contact 23, a relatively stiff spring finger 25 is arranged to bear against the end of the lamp opposite to the base, this finger having a slotted end to receive the sealing tip 26, Fig. 2, on the lamp.
- It will be observed that the main lamp 6 is supported with its axis extending transversely to the axis of the reflector 35 and that the auxiliary lamp 7 is substantially in vertical alinement with it but that its axis extends at approximately right angles to that of the main lamp 6 as well as extending in a direction transversely to the general direction of the axis of the reflector. This relationship of the lamps and the reflector, and particularly that between the main lamp and the reflector, is of advantage in reducing the size, and consequently the weight, of the casing or head piece required to support and house the lamps.
- Normally when the apparatus is in use the switch is in the position shown in Figs. 4 and 5 so that the main lamp 6 is lighted, and the auxiliary lamp 7 is "out" or unlighted. The latter lamp is used only in case of emergency. If the main lamp fails for any reason or is broken, the miner then lights the auxiliary lamp by turning the switch handle 20 until the movable switch member 17 engages the plate 24.
- Due to the fact that the cup member 8 of the socket for the main lamp is supported on a spring which is biased or tensioned outwardly away from the stationary contact 15, this socket member tends to hold the lamp downwardly away from the part 15 and thus to prevent the flow of current through the lamp. The lamp, however, is supported against this action of the spring by the free forked end of a spring arm 33 which is secured rigidly in the back of the casing. This arm will yield to permit the introduction or removal of the lamp 6 but it is sufficiently stiff to hold the lamp securely in its socket against the tension of the spring 9. It is obvious from an inspection of Fig. 3 that the arm 33 holds the lamp bulb 6 normally back against the reflector or in contact with the screw 37', in case the head of this screw projects beyond the reflector, the reflector and screw being equivalents so far as their func-

tion of aiding in the support of the bulb is concerned. In other words, the reflector and arm cooperate to hold the bulb in a very definite and substantially centered position with reference to the reflector.

The front end of the chamber in the casing 2 is closed by a glass or "lens" 27 which protects both lamps 6 and 7. While this glass front 27 does not, strictly speaking, perform the functions of a lens, it is ordinarily so referred to. It is held in its operative position by a bezel 28 having prongs or projections cooperating with several bayonet slots, one of which is shown at 29, Fig. 5. An extension 30 at the lower side of the bezel is provided with holes to receive a screw connecting the bezel with an extension 31 from the bracket 3, this screw serving to lock the bezel and bracket together. Additional holes are provided in the parts 30 and 31 so that they may be sealed together to prevent the opening of the casing without leaving behind evidence of such fact. A rubber gasket 32 is interposed between the glass 27 and the end of the casing 2.

If the lamp 6 should be broken, the cup member 8 of the socket would immediately move the lamp base downwardly, thus mechanically breaking the contact between the end terminal of the lamp and the stationary plate 15. This cuts off at once any flow of current through the lamp and consequently minimizes the danger of igniting mine "damp" or any other combustible gas surrounding the apparatus.

If the bulb of the lamp 7 should break, the spring arm 9 would immediately force the socket 8 away from the contact 23, thus mechanically breaking the circuit through this lamp.

A concave reflector 35 is located in the casing 2 immediately behind the lamp 6, the lamp preferably being approximately centered with reference to this reflector so that the maximum illumination afforded by the lamp is utilized. The auxiliary lamp 7 is at one side of this reflector, and the reflector, consequently, is not efficiently positioned with regard to it, but this is not objectionable for the reason that the lamp 7 is used only in emergencies. The reflector is held in its operative position by a screw 37' projecting through the center of the reflector and threaded into a small bracket 38, Figs. 4 and 5. Four holes are formed through the reflector in the construction shown, two to receive, respectively, the bases of the two lamps, and the other two to permit the passage therethrough of the spring arms 25 and 33, respectively.

A piece of sheet insulating material 40, such as oiled linen, fibre, or the like, is placed immediately behind the reflector to reduce the danger of short circuits.

If the bulb of either lamp should break, its

base would drop into the lower part of the chamber, and in order to prevent any danger of its short circuiting the terminals of the lamp 7 or its socket the reflector 35 is provided with a bulged portion 37, Fig. 2, which overlies and forms a shield or guard for the socket of the latter lamp. Such a guard obviously is not necessary for the lamp 6 because the base of the broken lamp would fall into the bottom of the lamp chamber.

It will now be understood that this invention provides a miner's lamp which affords for greater illumination than has been obtainable heretofore in commercial forms of lamps designed to be worn on the cap or other parts of the clothing. At the same time the size and weight of the apparatus has not been materially increased, and the expense of manufacture compares favorably with that of prior constructions. Provision has also been made for guarding against the various emergencies and accidents which are likely to arise.

While I have herein shown and described the best embodiment of my invention that I have so far devised, it will be understood that the invention may be embodied in other forms without departing from the spirit or scope thereof.

Having thus described my invention, what I desire to claim as new is:

1. In a miner's lamp, the combination of a head piece including a lamp casing, means for fastening said head piece to a cap or the like, an electric lamp mounted in said casing, a socket for said lamp arranged to release the lamp upon the breaking of the lamp bulb and a guard for preventing the base of a broken lamp from short circuiting the socket.

2. In a miner's lamp, the combination of a head piece including a lamp casing, means for fastening said head piece to a cap or the like, an electric lamp in said casing, a socket for said lamp arranged to release the lamp upon the breaking of the lamp bulb, and a reflector for said lamp, said reflector being provided with a guard associated with said socket in such a manner as to prevent the base of a broken lamp from short circuiting the socket.

3. In a miner's lamp, the combination of a head piece including a lamp casing, means for fastening said head piece to a cap or the like, an electric lamp mounted in said casing, a socket for said lamp arranged to release the lamp upon the breaking of the lamp bulb, a reflector for said lamp, said reflector having a guard overlying the socket of said lamp and serving to prevent the base of a broken lamp from short circuiting the socket.

4. In a miner's lamp, the combination of a head piece including a lamp casing, means for fastening said head piece to a cap or the like, a reflector in said casing, an incandescent lamp mounted in said casing in front of said

reflector, said lamp extending transversely to the axis of the reflector, a socket mounted in one side of said casing for receiving the base of the lamp and arranged to release the base automatically upon the breaking of the lamp bulb, and an arm mounted in said head piece and arranged to engage the end of said bulb, said arm serving to press said bulb backwardly against said reflector and cooperating with the reflector to hold said lamp in a substantially centered relationship to said reflector.

5. In a miner's lamp, the combination of a head piece including a lamp casing, means for fastening said head piece to a cap or the like, a concave reflector in said casing, a main electric lamp mounted in said casing in front of said reflector, a lamp socket in one side of said casing for supporting said lamp in a position with its axis extending transversely to the axis of said reflector, means cooperating with said socket to hold said lamp substantially centered with reference to said reflector, a second electric lamp of much smaller candle power than said main lamp, and means for supporting said second lamp in front of said reflector with its axis extending transversely to that of the main lamp.

6. In a miner's lamp, the combination of a head piece including a lamp casing, means for fastening said head piece to a cap or the like, a reflector in said casing, a main incandescent lamp mounted in an inverted position in said casing in front of said reflector, a socket mounted in the upper part of the casing for receiving the base of the lamp and arranged to release the base automatically upon breaking of the lamp bulb, means for engaging said lamp bulb to hold it in its operative position and in a substantially centered relationship to said reflector, a second incandescent lamp of smaller candle power than said main lamp mounted in said casing below said main lamp and substantially in vertical alinement therewith, and a socket for supporting said second lamp.
